UNITED STATES PATENT OFFICE.

ROBERT PETER MONCRIEFF AND JOHN MITCHELL MONCRIEFF, OF SOUTH SHIELDS, ENGLAND.

TEA-POT, COFFEE-POT, &c.

SPECIFICATION forming part of Letters Patent No. 451,862, dated May 5, 1891.

Application filed May 1, 1890. Serial No. 350,241. (No model.)

To all whom it may concern:

Be it known that we, ROBERT PETER MONCRIEFF, jeweler, and JOHN MITCHELL MONCRIEFF, civil engineer, subjects of the Queen of Great Britain, both residents of 20 Argyle Terrace, South Shields, in the county of Durham, England, have invented new and useful Improvements in Tea-Pots, Coffee-Pots, and other Similar Receptacles, of which the following is a specification.

This invention comprises certain improvements in tea-pots, coffee-pots, and other similar receptacles so constructed that their liquid contents are discharged by displacement. The liquid contents from receptacles of this character have hitherto been discharged only during the time the air-vent is closed and pressure maintained on the displacer, a relaxation of the pressure or an opening of the air-vent resulting in a cessation of the flow of liquid. In practice it has been found very inconvenient to keep the air-vent closed and simultaneously to maintain constant pressure on the displacer during the time the liquid is required to flow, and our invention is designed with the object of overcoming this inconvenience.

Our invention relates to the application of the siphon principle to receptacles from which the liquid contents have hitherto been discharged by displacement. When once the siphon is started the contents will continue to flow automatically until the desired quantity has been discharged, when the flow may be conveniently stopped by the production of a partial vacuum in the receptacle. This may be effected by closing the air-vent and withdrawing the displacer; and in order that our invention may be more fully understood and carried into practice we will now proceed to describe the same with reference to the accompanying drawing, which shows the section of a tea-pot constructed in accordance with our invention.

We provide the tea-pot with a spout constructed on the principle of the siphon—that is to say, the discharging-orifice of the outer leg A is at a lower level than the orifice K of the inner leg B.

In the drawing we have shown the outer

leg A curved to correspond with the curvature of the handle C; but the outer leg A may be made perfectly straight, or of a fanciful shape, as desired.

D is a displacer, which may form part of the lid of the vessel, and is capable of being slid up and down within the cylindrical casing E, the two contiguous faces of the displacer and casing being worked up as nearly true as possible, so that they fit each other practically air-tight. The knob F is provided with a central aperture G in direct communication with the inside of the tea-pot, so that the air may freely pass through the aperture G into and out of the tea-pot.

H is a strainer of ordinary construction. It forms no part of our invention and may be dispensed with, although we prefer to use something of this kind to prevent the tea-leaves from passing off with the tea.

To start the siphon the displacer D is raised with the aperture or air-vent G open. This allows the air to pass into the interior of the tea-pot through the aperture G. The said aperture G is now closed by the finger of the operator or by other suitable means and the displacer D is gently pressed inward, thus compressing the air within the tea-pot and forcing the liquid to completely fill the siphon-tube. The siphon having thus been started, the displacer D is then released and the air-vent unclosed, and the liquid will continue to flow automatically until the siphoning action is interfered with by the admission of air to the siphon-tube or by the production of a partial vacuum or other means. To stop the siphoning when sufficient has been drawn off, the vent G is closed and the displacer quickly raised, creating a partial vacuum in the tea-pot, which causes the withdrawal of the liquid from the tube and then stops the siphoning action. When more tea, coffee, or other liquid is required to be drawn off, the action of the siphon is again started, as before.

What we claim is—

1. A tea-pot, coffee-pot, or other similar receptacle, consisting of a vessel having an opening for the reception of a displacer adapted to cause a continuous flow of liquid from said receptacle upon inserting said displacer into

said opening and stop the flow of liquid upon creating a partial vacuum in said receptacle, and a siphon-spout communicating with the interior of said receptacle, substantially as 5 and for the purposes hereinbefore set forth.

2. A tea-pot, coffee-pot, or other similar receptacle, consisting of a vessel having an opening at the top, a displacer to fit said opening and provided with an aperture G, and a siphon- 10 spout communicating with the interior of said

vessel, these parts being arranged and constructed for joint operation substantially as hereinbefore specified.

ROBERT PETER MONCRIEFF.
JOHN MITCHELL MONCRIEFF.
